UNITED STATES PATENT OFFICE.

GEORGE A. MCILHENNY, OF WASHINGTON, DISTRICT OF COLUMBIA.

IMPROVEMENT IN LOCKS FOR PIPE-COUPINGS.

Specification forming part of Letters Patent No. 122,396, dated January 2, 1872.

To all whom it may concern:

Be it known that I, GEORGE A. MCILHENNY, of Washington, in the county of Washington and District of Columbia, have invented certain Improvements in Locks for Pipe-Couplings, of which the following is a specification, reference being had to the accompanying drawing.

My invention relates to locks for pipe-couplings, and consists of certain improvements upon the device for which Letters Patent No. 105,105 were granted me July 5, 1870, and especially in the manner of securing the device about the coupling of gas-pipes.

Figure 1 is a longitudinal cross-section of my device when open. Fig. 2 is a cross-section of the same when in position about the coupling. Fig. 3 is a top plan of the same, and Fig. 4 is a plan view of another method of hinging the parts of the device.

The special object of a lock for pipe-couplings, and particularly for gas-pipe couplings, is to secure it in place in such a manner that it cannot be removed and replaced by unauthorized persons without leaving some evidence of such removal and replacement.

As is well known, frauds are constantly being practiced upon gas companies by unprincipled consumers, who, between the monthly examinations of the meters by the agents of the companies, uncouple or disconnect the pipes and use the gas direct from the service pipes without allowing it to pass through the meter and afterward replace these connections before they can be detected. In order to prevent this fraudulent consumption of gas I have modified the construction of my patented lock above mentioned so that it can be secured in place by means of a pin held in place by wax impressed with the company's seal.

The case or shell A of the lock is constructed as described in my patent of July 5, 1870, above referred to, except that the free ends D and E of the semicircular parts B and C are also made semicircular, but without any inwardly-projecting flanges, such as are upon the parts B and C, as clearly shown in Figs. 1 and

2. In the ends D and E are circular partitions or plates G and H forming a part of the same, and so arranged that when the lock is clasped about the coupling-nut the circular plates G and H will lap by each other and a circular opening, α , in each come directly in line, so that a broad-headed pin, I, may be inserted, as clearly shown in Fig. 2; at the same time the ends, when thus brought together, form a cup above the pin-head, into which wax is poured in a melted state and the seal of the company impressed thereon, as shown in Fig. 3.

The operation, mode of applying, and utility of this improved device or lock is obvious.

When applied about the coupling connecting the gas-pipes with those passing through the meter, and then fastened by means of a pin held in place by the company's seal, it cannot be removed without breaking this seal; nor can it be replaced without using the seal; both of which acts can only be performed lawfully by a person duly authorized by the company.

It is obvious that the halves of the lock, instead of being hinged together, as in my previous patent, and as shown in Figs. 1 and 2, may be hinged or connected, as shown in Fig. 4, or in any other manner that will allow the parts to be opened and closed readily.

While the case or shell with the improvement above described is specially intended to prevent the fraudulent consumption of gas, yet it is obvious that it may be applied with advantage to all kinds of pipe-couplings when it is desirable to detect improper tampering with the same, and that it may be constructed of any form or size required to embrace the coupling.

Having thus described my invention, what I claim is—

A lock for pipe-couplings, constructed substantially as herein described, in combination with a seal of wax or its equivalent, as and for the purpose herein set forth.

GEORGE A. MCILHENNY.
